Primary Examiner — Elizabeth J Oswecki(74) *Attorney, Agent, or Firm* — Knobbe Martens Olson
& Bear LLP(57) **CLAIM**

The ornamental design for an item collection receptacle, as shown and described.

DESCRIPTION

FIG. 1 is a perspective view of an item collection receptacle showing our new design;
 FIG. 2 is a front view thereof;
 FIG. 3 is a back view thereof;
 FIG. 4 is a top view thereof;
 FIG. 5 is a bottom view thereof;
 FIG. 6 is a left side view thereof; and,
 FIG. 7 is a right side view thereof.
 Broken lines are used to illustrate features which form no part of the claimed design.
